BOBBIN AND METHOD OF MAKING THE
SAME

Paul P. Muller, Paterson, N. J.

Application March 1, 1933, Serial No. 659,092

8 Claims. (Cl. 242—119)

This invention relates to spools, bobbins and the like (hereinafter termed bobbins) and particularly to that class of such devices in which the barrel and its head or heads are assembled parts. The object is to provide, at the minimum of expense, for greater durability and strength than bobbins of this class usually have and in particular to insure that the head or heads shall be so firmly secured to the barrel as to be practically integral therewith, this being very desirable where in the drying of wet silk yarn wound thereon the bobbin has to withstand great longitudinal pressure of the wound mass as, in the drying, its windings contract and so set up such pressure. The improved bobbin herein set forth has shown in testing apparatus the ability to withstand a pressure exerted outward against the head of as much as 1800 lbs., and even at that pressure the head would become bent before its anchorage to the barrel would give way. Further, the construction is such that the parts are secure against coming apart due to rough handling or the shrinkage of the selected wood or equivalent material employed, even after long service. Thus the improved bobbin is superior to any bobbin heretofore known to me.

In the drawing,

Fig. 1 shows partly in side elevation and partly in section one form of a bobbin according to this invention, the assembly at its lower end being shown complete and at its upper end partially effected;

Fig. 2 is an end view of the bobbin;

Fig. 3 is a transverse sectional view of one of its heads and an attaching collar therefor;

Fig. 4 is a sectional view of one end of another form of the bobbin in partially assembled state;

Fig. 5 is an inside view of the head and collar of such form; and

Fig. 6 a transverse sectional view of the latter head and collar.

1 is a barrel, which may be of some more or less yielding material, as wood, having its bore 2 enlarged at each end, as at 3, and having at each end an integral projection 4 concentric with the bore and thus annular and in the example formed by providing a channel 5, also concentric with the bore, in the end of the barrel and removing material of the barrel outwardly of the channel for a portion only of its depth, or for a depth equal to the thickness of the head.

Each head is formed as a disk 6, here of fiber, centrally apertured at 7.

At 8 is a cylindrical collar of substantially unyielding material, as metal, having in its aper-

ture what I term inward impression-forming means adapted to impress and form an interlock with the barrel. Such means in Figs. 1 to 3 is screw-threading 9, and in Figs. 4 to 6 it is internal ribs 10, preferably interrupted at 11 and in such manner that the interruption in any one rib is offset with relation to that of the next rib. The collar has at one end an exterior flange 12 which, by notching the flange at intervals, as at 13, affords peripheral keys. Each head and its collar may be assembled to form a flange-forming structure for the bobbin by subjecting these parts to pressure, with the collar in the aperture of the head, and so that the mentioned keys embed themselves in the head and remain lapping it as shown.

If the flange-forming or head-including structure is of the type of Figs. 1 to 3 it may be first screwed onto the projection 4, cutting its own thread, at least to partial depth as shown in Fig. 1. If it is of the type of Figs. 4 to 6 it is slipped over the head, which it preferably should, however, snugly fit. In either case it bears against the end face of the barrel around the projection.

14 is a plug having a cylindrical head 14a of somewhat greater diameter than the barrel bore at 3, a downward taper 14b next below the head and an axial bore 14c. This plug has such diameter that when employed as will appear it will cause yielding of the material of the barrel.

When the flange-forming structure 6—8 has been assembled with the barrel as stated the plug is introduced to the barrel bore at 3 and driven home, or so that its head 14a enters the bore. Thereby the plug (to wit, its head) presses the annular projection 4 radially outward against the collar, preferably to such an extent that said projection is not only compressed and compacted between the plug and the ribs (thus impressing the ribs in portion 4 and setting up a positive interlock between said portion and the collar) but between said portion and the cylindrical surface portions of the collar lying between its ribs, its general thickness being reduced as may be seen by a comparison of the upper and lower ends of the bobbin in Fig. 1. In fact, an enlarging distortion or expansion of the portion 4 actually takes place (even where the collar is threaded and initially screwed onto the barrel, provided its threads do not enter the barrel material their full depth), as also shown in Fig. 1 at the bottom, but if for the barrel some tough material, such as maple wood commonly used for the purpose, is employed this distortion occurs without dis-

rupting the connection between the portion 4 and the body of the barrel.

My invention distinguishes in the following respects from bobbins of its class in which the displacement of the bored end of the barrel into pressing relation to the flange-forming structure embracing said end is depended on to unite them:

When such an expander as the portion 14a of the element 14 is driven into the bored end of the barrel it progressively expands to substantially the same extent and into gripping relation to the aperture surface of the flange-forming structure the portions of said end lying in the successive planes through which the expander passes 15 and which are within the zone of said structure.

The impression forming means comes into action to form the interlock by a novel radial displacement of the barrel end, which is already in telescoped relation to the collar, as distinct 20 from a scoring or grooving action incident to forcing one of these parts into telescoped relation to the other.

The pressure developed is a material factor in resisting displacement of the collar rotatively as 25 well as axially, though if the interrupted ribs 10 of Figs. 4 to 6 be used the pressure causes the material of portion 4 to be impressed into the interruptions 11, establishing a positive interlock or obstruction against such rotary displacement.

It has been proposed in this art to employ a flange-forming structure having a collar receiving a portion of the barrel, but not, so far as I am aware, where the collar coacts with a plug or equivalent as herein set forth.

When the plug is to be introduced it may desirably be coated with glue.

It is not indispensable that the parts of the flange-forming structure be united with the barrel as a pre-formed assembly, as herein described.

Having thus fully described my invention what I claim is:

1. The herein-described method of fixedly uniting, with a bobbin barrel having a yielding bored end, a flange-forming structure having a substantially unyielding apertured center portion in telescoped relation to said end and impression-forming means in the aperture projecting toward said end which consists in radially 50 displacing said end circumferentially thereof until it is impressed by said means.

2. The herein-described method of fixedly uniting, with a bobbin barrel having a yielding bored end, a flange-forming structure having a substantially unyielding apertured center portion receiving said end and inward impression-forming means in its aperture which consists in expanding said end until it is impressed by said means.

60. 3. The herein-described method of fixedly uniting, with a bobbin barrel having a yielding bored

end, a flange-forming structure having a substantially unyielding apertured center portion receiving said end and inward impression-forming means in its aperture which consists in driving into the bore of said end in frictionally retained relation thereto a plug having such diameter and compression-resistance as to expand said end until it is impressed by said means.

4. A bobbin comprising a barrel of yielding material having a bored end, an apertured head having its aperture receiving said end, a substantially unyielding collar in said aperture and receiving said end, said collar and barrel having means to limit displacement of the head lengthwise of the barrel in each direction, and a plug driven into the bore of said end and having a portion in the zone of the head holding said end pressed radially outwardly against the collar.

5. A bobbin comprising a barrel of yielding material having a bored end, an apertured head having its aperture receiving said end, an unyielding collar in said aperture and receiving said end and having in its aperture inward impression-forming means, said collar and barrel having means to limit displacement of the head lengthwise of the barrel in each direction, and a plug driven into the bore of said end and having a portion in the zone of the head holding said end pressed radially outwardly against said means and impressed by the same.

6. The herein-described method of fixedly uniting, with a bobbin barrel of yielding material having a bored end, an apertured flange-forming structure receiving said end in its aperture which consists in forcing into the bore of said end and through the zone of said structure an expander having such diameter as progressively to expand to substantially the same extent and into gripping relation to the aperture surface of said structure portions of said end lying in the successive planes through which the expander passes within said zone.

7. The herein-described bobbin comprising a barrel of expandable material and an annular flange-forming structure embracing one end of the barrel, said end being expanded to substantially the same extent in various planes perpendicular to the axis of the barrel and within the zone of said structure and into gripping relation to the latter.

8. The herein-described bobbin comprising a barrel of expandable material; an annular flange-forming structure embracing one end of the barrel, said end being expanded to substantially the same extent in various planes perpendicular to the axis of the barrel and within the zone of said structure and into gripping relation to the latter and a plug in said end maintaining the same expanded.
